UNITED STATES PATENT OFFICE.

GEORGE W. TEASDALE, OF ST. LOUIS, MISSOURI.

DISAPPEARING BED.

1,313,760.

Specification of Letters Patent.

Patented Aug. 19, 1919.

Application filed January 6, 1919. Serial No. 269,855.

To all whom it may concern:

Be it known that I, GEORGE W. TEASDALE, a citizen of the United States, residing at St. Louis, Missouri, have invented a certain new and useful Improvement in Disappearing Beds, of which the following is a full, clear, and exact description, such as will enable others skilled in the art to which it appertains to make and use the same.

10 This invention relates to a disappearing bed of the same general type described in my pending application for patent Serial No. 149,540, filed February 19, 1917, which bed comprises an operating mechanism for raising and lowering the bed into and out of an elevated compartment arranged outside of the room in which the bed is used.

20 The main object of my present invention is to provide a disappearing bed of the type referred to in which the operating mechanism is so constructed that the bed will travel in a substantially horizontal plane instead of in an arc when it is being introduced into and withdrawn from the elevated 25 compartment, thereby enabling the height or vertical depth of said compartment to be reduced.

Another object is to provide a disappearing bed of the particular type referred to in which the operating mechanism is so constructed that the bed will be spaced some distance away from the wall of the room when the bed is raised slightly above the floor, thus providing ample space between 35 the bed and the wall for the person who makes up the bed or arranges the bed clothes in proper position on the bed.

Another object is to provide a disappearing bed of the type referred to that will travel at a substantially uniform rate of speed when it is being moved into and out of operative position, notwithstanding the fact that the operating mechanism is provided with a counterweight which at times 45 is considerably out of balance with the bed.

To this end I have devised a disappearing bed whose operating mechanism comprises two pivotally mounted actuating members for raising and lowering the bed into and out of an elevated compartment and for holding the bed in a horizontal position while it is being raised and lowered, and means for causing the bed to move or shift bodily relatively to said members in such 55 a manner, when it is being raised and lowered, that it will travel successively in two

paths at right angles to each other instead of in an arc, said means and members being so constructed and combined that the bed will move in a substantially vertical 60 path when it is being raised and lowered and will move in a horizontal path when it is being introduced into and withdrawn from the elevated compartment.

A manually operable device is preferably 65 employed for swinging the actuating members that raise and lower the bed and one of said members is provided with a counterweight so as to assist the operator in raising and lowering the bed. Owing to the 70 fact that the bed shifts or moves bodily relatively to the actuating members while it is being raised and lowered, the bed is considerably out of balance with the counterweight at certain times. In order to compensate for this unbalancing action, I have 75 provided the operating mechanism with a means that becomes operative automatically during the operation of raising and lowering the bed to offer sufficient resistance to 80 the movement of the manually operable device which turns the actuating members to cause the bed to travel at a substantially uniform rate of speed, instead of jumping or moving abruptly, as would be apt to 85 occur if no means were provided for counteracting the effect produced by the bed overbalancing the counterweight, or the counterweight overbalancing the bed. In the form of my invention herein shown 90 compression springs are used for setting up the resistance above referred to, but I wish it to be understood that various other means could be employed for this purpose without departing from the spirit of my invention. 95

Figure 1 of the drawings is a view, partly in vertical section and partly in elevation, illustrating a disappearing bed constructed in accordance with my invention, the bed 100 being shown in full lines in its operative position and in dotted lines in its inoperative position, and also one position that it assumes when it is being raised and lowered.

Fig. 2 is a side elevational view of the bed 105 proper, looking at the side wall of the room adjacent which the bed is arranged when it is in its operative position.

Figs. 3 and 4 are front elevational views of the bed proper, on an enlarged scale, 110 for the purpose of illustrating the operation of the mechanism that shifts or moves

the bed bodily relatively to the pivotally mounted actuating members; and

Fig. 5 is a horizontal sectional view, taken on approximately the line 5—5 of Fig. 3.

- 5 Referring to the drawings which illustrate the preferred form of my invention, A designates the bed proper, B designates the room in which the bed is arranged when it is in use, C designates a compartment arranged outside of said room and located in a higher horizontal plane than the floor of the room, D a closet or low-ceilinged room, above which the compartment C is arranged, 1 a transom or hinged door that forms a closure for the elevated compartment C and 2 a hollow partition or wall in the closet D in which the operating mechanism of the bed is housed when the bed is not in use, said partition 2 having a slot or pocket 20 whose outer end terminates in a vertical slot or opening in the side wall of the room adjacent which the bed is arranged when the bed is in use, as shown in full lines in Fig. 1.
- 25 The mechanism for withdrawing the bed from the compartment C and moving it downwardly onto the floor of the room B, when it is desired to use the bed, and for thereafter moving the bed upwardly into said compartment, is similar to the operating mechanism of the bed described in my pending application previously referred to, in that it comprises a lever or pivotally mounted actuating member E that is rigidly connected to a horizontally-disposed shaft 3 journaled in the partition 2, a second lever or pivotally mounted member G pivotally connected at 4 to the partition 2, a sprocket chain 5 that travels over a sprocket wheel 6 on the upper end of the lever G and over a sprocket wheel 7 rigidly connected to the shaft 3, a crank arm or manually operable actuating device 8 connected to a pinion 9 that meshes with a gear 10 on the shaft 3, and a system of links and levers operated by a cam slot in the gear 10 for opening and closing the transom 1 of the elevated compartment C. The lever E is provided with a counterweight 11 and with a forwardly-projecting arm 12 that is pivotally connected at 13 to a frame 14 on which the bed is mounted and the lever G is also provided with a forwardly-projecting arm 15 which is pivotally connected at 16 to the frame 14.
- 55 The operating mechanism of my present bed differs materially, however, from the operating mechanism of the bed described in my pending application above referred to, in that the bed A is mounted on the frame 14 in such a manner that it can shift or move bodily relatively to said frame, and means is provided for moving it relatively to the frame 14 in such a manner, when the bed is being raised and lowered, that the bed travels in a substantially horizontal path

when it is being introduced into and withdrawn from the compartment C, and also stands a considerable distance away from the side wall of the room when it is raised slightly above the floor. As shown in the drawings, particularly Fig. 2, the frame 14 extends transversely of the bed and is provided at its upper end with a guide 17 of substantially dove tail shape in cross section that receives a transversely-disposed member 18 on the bed that is arranged at the center of the bed, the member 18 being so designed that it can slide freely in the guide 17 on the frame 14. The angularly-disposed arm 12 on the lever E is provided with a segmental gear 19 that is concentric with the pivot 13 that joins the lever E to the frame 14, said segmental gear meshing with a rotatable pinion 20 on the frame 14. The pinion 20 is provided with an arm 21 that is connected by means of a link 22 with the right hand end of the transversely-disposed member 18 on the bed, as shown clearly in Fig. 1. When the manually-operable device or crank arm 8 is turned to swing the levers E and G upwardly to raise the bed from the floor of the room and introduce it into the elevated compartment C, the arm 21 on the pinion 20 rotates in clockwise direction, due to the movement that the segmental gear 19 imparts to the pinion 20. When the bed is in its operative position on the floor of the room, as shown in full lines in Fig. 1, the frame 14 stands at the center of the bed. When the actuating members E and G start to swing upwardly, however, the free end of the arm 21 starts to move to the right, looking at Fig. 1, thereby causing the bed A to move to the right relatively to the frame 14, the arm 21 being so proportioned that the bed A will stand far enough away from the side wall of the room, when the bed is raised slightly above the floor, to permit a person to stand between the bed and the side wall of the room. The arm 21 continues to revolve in clockwise direction as the bed moves upwardly, and just about the time the bed comes into horizontal alignment with the compartment C, the arm 21 passes its outward dead center, and thus shifts or moves the bed bodily in the opposite direction relatively to the frame 14, the parts being so designed and arranged that the bed will travel in a horizontal path, to the left, relatively to the frame 14, while it is being introduced into the compartment C. When the levers E and G are swung downwardly to arrange the bed in operative position in the room, the bed A travels in a horizontal path relatively to the frame 14 until it clears the front edge of the floor or bottom of the compartment C. Thereafter, it moves downwardly in a substantially straight, vertical path until the arm 21 passes its inward dead center and moves

the bed to the left so that it is in close proximity to the side wall of the room by the time it reaches the floor. An operating mechanism of the construction above described is desirable in two respects; first, it causes the bed to be spaced far enough away from the side wall of the room, when the bed is raised slightly above the floor, to provide ample space between the bed and the side wall of the room for the person who makes up the bed; and second, it makes it possible to house the bed in a compartment C which is only a trifle higher or deeper than the end frames of the bed, this, of course, being due to the fact that the bed travels in a substantially horizontal path instead of in an arc while it is being introduced into and withdrawn from the compartment C.

In view of the fact that the bed A shifts or moves bodily relatively to the frame 14, while the bed is being raised and lowered, there are certain times in the cycle of operations when the bed considerably overbalances the counterweight 11, and there are also times when the counterweight 11 considerably overbalances the bed. Unless means were provided for counteracting this unbalancing action, the bed would jump or move abruptly, when it is being raised and lowered, if the operator did not use great care in regulating the pressure applied to the manually-operable device 8 which turns the levers E and G. I prefer to construct the bed in such a manner that it will move at a substantially uniform rate of speed, when it is being raised and lowered, by simply turning the crank 8 in a natural manner; in other words, without requiring the operator to carefully graduate or vary the pressure that is applied to said crank at the times when the bed and counterweight are moving into and out of the balance with each other. In the form of my invention herein shown this is accomplished by providing the operating mechanism with two compression springs 23 and 24 which are so arranged that they will coöperate with devices 23^a and 24^a on the bed to set up a resistance to the normal movement of the manually-operable actuating device 8 at certain times in the cycle of operations in moving the bed into and out of operative position.

As shown in Figs. 3, 4 and 5 of the drawings, the frame 14 is provided at its upper end with an ear or lug 25 that projects laterally from one side of same. This ear or lug is used as a support for a lever 26 that extends longitudinally of the frame and which swings in a horizontal plane, the lever 26 being provided on its top side with a relatively long, vertically-disposed bearing 27 through which a pintle or pivot pin 28 passes so as to connect the lever to the lug 25 on the frame 14. The compression springs 23 and 24 previously referred to are ar-

ranged at the opposite ends of the lever 26, being mounted in pockets 29 on said lever. The segmental gear 19 on the angularly-disposed arm of the pivotally-mounted actuating member E is provided with two cam blocks 30 and 31 which are so arranged that they will strike the lever 26 at certain times in the cycle of operations of the mechanism and move said lever so as to render the springs 23 and 24 operative and inoperative. When the bed is in its operative position on the floor of the room the lever 26 occupies the position shown in Fig. 5 and the cam blocks 30 and 31 on the segmental gear 19 stand in the position shown in Fig. 3. When the bed starts to move upwardly neither of the springs 23 or 24 will function, due to the fact that the spring 24, which resists movement of the bed to the right, is then in such a position that it will not be engaged by its coöperating device 24^a on the bed when the bed moves to the right, and the spring 23 is at this time spaced away from its coöperating abutment 23^a. When the bed, in its further upward travel, moves to the left relatively to the frame 14, the spring 23, which is then in alinement with its coöperating device 23^a on the bed, will offer resistance to the bed and tend to prevent the arm 21 and link 22 from moving the bed to the left. Accordingly, the pinion 20 starts to slow down and puts sufficient additional load on the turning crank 8 to make it necessary for the operator to exert a force or pull on the starting crank equal to or greater than that which was required when the bed was at its extreme right hand position, and consequently, overbalanced the counterweight considerably. As the bed moves toward the right relatively to the frame 14, to the intermediate dotted position shown in Fig. 1, the resistance set up by the spring 23 is decreased or withdrawn, due to the fact that the abutment 23^a is moving to the right or away from said spring. Continued upward movement of the bed causes the arm 21 to rotate and move the bed to the left just as it comes into approximate alinement with the elevated compartment C. The first half of this leftward movement of the bed is free of any resistance, due to the fact that the abutment 23^a is now moving toward the spring 23, but is not in engagement therewith. Just as the bed reaches the approximate center of its leftward movement, as it is entering the compartment C, the cam block 31 rides under the left hand side of the lever 26 and rocks said lever so as to throw the spring 23 out of alinement with the abutment 23^a, but immediately the cam block 30 comes into play and rocks said lever in the opposite direction so as to restore the same to the position shown in Fig. 5, the position it has occupied during its upward travel. By the time the bed reaches its inoperative position

in the compartment C the spring 23 will have been fully compressed, as shown in Fig. 4, and will remain in this compressed condition until the crank 8 is turned in the reverse direction to lower the bed. Due to the fact that the spring 23 is under compression when the crank A¹ is turned to lower the bed, said spring will exert pressure on the bed in a direction tending to move it to the right, thus assisting the operator in starting to move the bed downwardly. Shortly after the segmental gear 19 starts to revolve relatively to the frame 14, during the operation of lowering the bed, the cam block 31 strikes 15 the lever 26 and shifts said lever into such a position that the spring 24 thereon is arranged in alinement with its coöperating device 24^a on the bed, and the spring 23 at the opposite end of said lever is moved out 20 of alinement with its coöperating device 23^a on the bed. Thereafter, on the downward movement of the bed, the spring 24 will offer resistance to movements of the bed to the right, thus requiring the operator to exert 25 substantially the same pull or force on the crank 8 when the bed is in its right hand position with respect to the frame 14, as is required when the bed is in its left hand position. Just as the bed nearly completes its 30 downward movement, the cam block 31 rides under the right hand side of the arm 26 and shifts said arm laterally into the position shown in Fig. 5, so that the spring 23 will be in readiness to coöperate with its 35 abutment 23^a when the bed is again raised from the floor of the room B.

From the foregoing it will be seen that I have devised a disappearing bed in which the movement of the bed into and out of use 40 position is in two substantially straight paths at an angle to each other, instead of in an arcuate path, as described in my pending application above referred to, thus enabling the size of the bed compartment 45 above the floor to be materially reduced, the mechanism for accomplishing this also being utilized to force the bed outwardly a considerable distance away from the adjacent wall when said bed has been raised only 50 slightly from the floor. Furthermore, novel means have been provided for overcoming a condition incident to the construction just referred to, namely, for compensating for the periods in the cycle of operations of moving the bed into and out of use position when 55 said bed and counterweight are considerably out of balance.

Having thus described my invention, what I claim and desire to secure by Letters Patent, is:

1. A disappearing bed, comprising a frame, a bed mounted on said frame, mechanism for moving said bed into and out of a compartment arranged outside of the room 65 in which the bed is used and above the floor

of said room, and means connecting said bed and frame so that said bed is caused to move horizontally in both directions with respect to said frame during the operation of moving the bed and frame. 70

2. A disappearing bed, comprising a frame, a bed slidably mounted on said frame, a mechanism for moving said frame and bed into and out of an elevated compartment in which the bed is adapted to be arranged 75 when the bed is not in use, and means connecting said bed and frame whereby said bed is caused to move horizontally in one direction or the other across said frame when said frame is being moved. 80

3. A disappearing bed, comprising a bed, mechanism for moving said bed into and out of an elevated compartment arranged outside of the room in which the bed is adapted to be used, and means whereby said bed is caused to travel upwardly in a substantially straight line and then horizontally in a substantially straight line as said bed is being moved from said room to said elevated compartment. 85

4. A disappearing bed, comprising a frame, a bed slidably mounted on said frame, mechanism for moving said frame in an arcuate path from the room in which the bed is used to an elevated compartment 95 outside of said room, and means connecting said frame and bed in such a manner that said bed is caused to move alternately in one direction or the other transversely of said frame while said frame is in motion. 100

5. A disappearing bed, comprising a frame, a bed slidably mounted on said frame, means for moving said frame in an arcuate path from the room in which the bed is used to an elevated compartment arranged outside of said room, and means connecting said frame and bed whereby said bed is caused to travel in a substantially inverted L-shaped path while said frame is traveling in an arcuate path. 110

6. A disappearing bed, comprising a frame, a bed slidably mounted on said frame, mechanism for moving said frame in an arcuate path from the room in which the bed is used to an elevated compartment arranged outside of said room, means for moving said bed transversely of said frame when said frame is in motion, a counterweight on said mechanism that balances the weight of said bed and frame when said bed 115 is arranged centrally with respect to said frame, and means for compensating for the unbalanced condition when the bed is moved transversely of said frame in either direction. 120

7. A disappearing bed, comprising a frame, a bed slidably mounted on said frame, mechanism for moving said frame in an arcuate path from the room in which the bed is used to an elevated compartment out- 125 130

side of said room, means for causing the bed to reciprocate transversely across said frame when said frame is in motion, means for resisting movement of said bed in one direction when said bed is moved upwardly, and means for resisting movement of said bed in the opposite direction when said bed is being lowered from said elevated compartment into the room in which said bed is used.

8. A disappearing bed, comprising a frame, a bed mounted on said frame so as to be movable transversely thereof, mechanism for moving said frame and bed from the room in which the bed is used to an elevated compartment located outside of said room, said mechanism being so designed that it will move the frame in an arcuate path and also maintain the same in a horizontal position while in motion, and means for causing the bed to reciprocate transversely across said frame while the frame is in motion.

9. A disappearing bed, comprising a frame, a bed mounted on said frame so as to be movable transversely thereof, mechanism for moving said frame in an arcuate path from the room in which the bed is used to an elevated compartment located outside of said room, means for causing said bed to reciprocate transversely across said frame while said frame is in motion, and means for resisting this crosswise movement of the bed with respect to the frame in one direction when the frame and bed are moving upwardly and in the opposite direction when said frame and bed are moving downwardly from said compartment to the room in which the bed is used.

10. A disappearing bed, comprising a frame, a bed mounted on said frame so as to move transversely thereof, mechanism for moving said frame in an arcuate path from the room in which the bed is used to an elevated compartment located outside of said room, means for causing said bed to reciprocate transversely of said frame while said frame is in motion, and coiled springs that are adapted to be interposed between said frame and bed to offer resistance to relative movement therebetween at certain times during the cycle of operations of moving the frame and bed into and out of said elevated compartment.

11. A disappearing bed, comprising a frame, a bed mounted on said frame so as to be movable transversely thereof, mechanism for moving said frame and bed into and out of an elevated compartment arranged outside of the room in which the bed is used, means for causing said bed to reciprocate transversely of said frame while said frame is in motion, and means for offering resistance to relative movement of said frame and bed at certain periods in the cycle of operations of moving the frame and bed into and out of said elevated compartment.

tions of moving the frame and bed into and out of said elevated compartment.

12. A disappearing bed, comprising a frame, a bed mounted on said frame so as to be movable transversely thereof, mechanism for moving said frame and bed into and out of an elevated compartment located outside of said room, means for causing said bed to reciprocate transversely of said frame while said frame is in motion, a pivotally mounted arm arranged on said frame and provided at each end with a coiled spring, abutments on said bed that are adapted to coöperate with said springs, and means for rocking said arm so that one or the other of said springs will be compressed by its coöperating abutment at certain periods during the cycle of operations of moving the frame and bed into and out of said elevated compartment.

13. A disappearing bed, comprising a frame, a bed mounted on said frame so as to be movable transversely thereof, mechanism for moving said frame and bed into and out of an elevated compartment located outside of said room, means for causing said bed to reciprocate transversely of said frame while said frame is in motion, a pivotally mounted arm arranged on said frame and provided at each end with a coiled spring, abutments on said bed that are adapted to coöperate with said springs, and cam blocks actuated by said mechanism for rocking said arm so that one or the other of said springs will be compressed by its coöperating abutment at certain periods during the cycle of operations of moving the frame and bed into and out of said elevated compartment.

14. A disappearing bed, comprising a frame, a bed mounted on said frame so as to be movable transversely thereof, mechanism for moving said frame and bed into and out of an elevated compartment located outside of said room, a crank arm on said frame that is rotated by said mechanism when said frame is in motion, and a link connecting said crank arm to said bed whereby said bed is caused to reciprocate transversely of said frame when said frame is being moved by said mechanism.

15. A disappearing bed, comprising a frame provided with a transverse guideway, a bed having a portion that is adapted to slide in said guideway, a pivotally mounted lever having its outer end pivoted to said frame so that rotation of said lever will raise said frame and bed from the room in which the bed is in use to an elevated compartment arranged outside of said room, a gear wheel on the outer end of said lever that meshes with a pinion journaled on said frame, a crank arm on said pinion, and a link connecting said crank arm to said bed so that said bed is caused to reciprocate

across said frame when said frame is being moved by said lever.

16. A disappearing bed, comprising a frame, a bed mounted on said frame so as to move transversely thereof, a mechanism for moving said frame and bed from the room in which the bed is used to an elevated compartment arranged outside of said room, means for causing said bed to reciprocate transversely across said frame when said frame is in motion, an abutment on each side of said bed, and a spring arranged at each side of said frame, one of said springs being adapted to coöperate with one of said abutments when the frame and bed are traveling upwardly, and the other of said springs coöperating with the other abutment when the frame and bed are traveling downwardly.
17. A disappearing bed, comprising a

frame, a bed mounted on said frame so as to move transversely thereof, a mechanism for moving said frame and bed from the room in which the bed is used to an elevated compartment arranged outside of said room, means for causing said bed to reciprocate transversely across said frame when said frame is in motion, an abutment on each side of said bed, and a spring arranged at each side of said frame, one of said springs being adapted to coöperate with one of said abutments when the frame and bed are traveling upwardly, and the other of said springs coöperating with the other abutment when the frame and bed are traveling downwardly, one of said springs being under compression when the bed is in one of its positions at rest so as to assist in the initial movement of said bed.

GEORGE W. TEASDALE.
